UNITED STATES PATENT OFFICE.

WILLIAM S. REED, OF SCALP LEVEL, PENNSYLVANIA.

DUMPING-WAGON.

SPECIFICATION forming part of Letters Patent No. 269,539, dated December 26, 1882.

Application filed October 2, 1882. (No model.)

To all whom it may concern:

Be it known that I, WILLIAM S. REED, a citizen of the United States, residing at Scalp Level, in the county of Cambria and State of Pennsylvania, have invented a new and useful Dumping-Wagon, of which the following is a specification, reference being had to the accompanying drawings.

Figure 1 is a plan view of the running-gear of my improved dumping-wagon. Fig. 2 is a longitudinal vertical sectional view of the wagon complete. Fig. 3 is a side view, showing the box in position for dumping. Fig. 4 is a detail view.

Corresponding parts in the several figures are denoted by like letters of reference.

This invention relates to dumping-wagons for general use; and it consists in certain improvements in the construction of the same, which will be hereinafter fully described, and particularly pointed out in the claims.

In the drawings hereto annexed, A represents the front and B the hind axle of my improved dumping-wagon.

C C are the hounds secured upon the front axle, and which support the sand-board D, upon which the bolster E is mounted, as shown, and held by means of the king-bolt F.

G G are the rear hounds, and H the rear bolster.

I is the reach, the rear end of which rests upon the axle B, under bolster H, extending from thence forward between the hounds G, to the front ends of which it is secured by a transverse bolt, J. In front of bolt J the reach I has a longitudinal vertical slot, K, which extends to near the front end, and through which the king-bolt F passes, as shown.

L is a U-shaped plate or bail, pivoted upon the king-bolt and extending over the front end of the reach, to which it may be connected by a detachable vertical bolt, M.

N is a beveled tooth or catch, secured to the rear side of the sand-board D; and O is a hooked catch or latch, hinged upon the reach I near its middle, and capable of engaging the tooth N, as will be presently described.

P P are brackets secured to the rear side of the rear axle, B, and bolster H, and having bearings for the axle of a transverse roller, Q, which is raised slightly above the level of bol-

ster H. Springs R, secured on the upper sides of the brackets P, serve to hold said roller in place detachably. Upon its front side the bolster H is provided with lugs S.

55

T is a rod or brace extending from near the center of the reach to the bolster H, as shown.

U is the wagon-box, which is provided on its under side with a clamp, V, catching over the front bolster, and with a hinged loop, W, 60 sliding upon the brace T. To the sides of the wagon-box are pivoted levers X X, connected under said box by a rod, Y.

The operation of my invention will be readily understood from the foregoing description, 65 taken in connection with the drawings hereto annexed. When the dumping-place is reached the bolt M is removed and the plate or bail L swung aside.

The hind wheels are then locked by means of an ordinary brake or other suitable mechanism, and the horses are then backed. This will cause the front part of the running-gear, which has been disconnected from the reach, to move in a rearward direction with the wagon-box, which slides upon 70 the roller Q, the reach passing between the front hounds and the tongue, and the king-bolt sliding in the slot K in the reach. When the wagon-box has moved back a sufficient distance the levers X take under the lugs S, thus 75

tilting the box and dumping the load. The loop W, which encircles the brace T, keeps the box from dropping off. At the same time the catch N and latch O have been thrown into engagement with each other, thus enabling the 80 wagon to be driven up for a short distance with the box tilted, in order to drop or dump the load completely. The catch N is then disengaged, the box returned to its original position, the horses driven up so as to properly adjust the running-gear, the plate L and bolt M 85 adjusted, and the wagon is then ready for another load.

By removing the box the running-gear of this wagon may be readily adapted for hauling and dumping lumber and the like.

I claim and desire to secure by Letters Patent of the United States—

1. The combination of the axle A, hounds C C, sand-board D, bolster E, king-bolt F, 100 reach I, heading-slot K, U-shaped plate or bail L, swiveled upon the king-bolt, and ex-

tending over the end of the reach, and the bolt M, as set forth.

2. The combination, with the reach I, having slot K and hinged hook O, of the front running-gear connected to said reach by the king-bolt sliding in slot K, and the beveled catch N, secured to the rear side of the sand-board so as to be capable of engaging hook O, as set forth.

- 5 3. The combination of the running-gear, the brace T, connecting the reach with the rear bolster, and the wagon-box having on its under side a hinged loop encircling said brace T, as set forth.
- 10 4. The combination of the running-gear, the

lugs S upon the front side of the rear bolster, and the wagon-box having levers X X, connected under said box by a rod, Y, as and for the purpose set forth.

5. The brackets P, secured, as described, to the rear axle and bolster, and having springs R and bearings for the detachable roller Q, as set forth.

In testimony that I claim the foregoing as my own I have hereto affixed my signature in presence of two witnesses.

WILLIAM STRATTON REED.
